UNITED STATES PATENT OFFICE.

EUGENE E. CLEMENTS, OF NEW HAVEN, CONNECTICUT, ASSIGNOR TO L. CANDEE & COMPANY, OF NEW HAVEN, CONNECTICUT, A CORPORATION OF CONNECTICUT.

BUCKLE-STRAP SEVERING AND ASSEMBLING MACHINE.

Application filed May 7, 1926. Serial No. 107,335.

This invention relates to a machine for cutting off strips of material from a continuous length and assembling the same in inter-linked relation with other articles.

5 In the rubber art, more particularly in the making of rubber footwear, such as arctics or gaiters, fasteners are used composed of complementary buckle elements. Each of these buckle elements is provided with an eye 10 at its rear end, and in assembling them on articles a strap formed of rubber coated fabric is inserted through the eye and the projecting ends of the strap then doubled over on each other and rolled together. The 15 rolled together ends are then inserted between rubber or rubberized plies of the article to which the buckles are to be applied, and in vulcanization the straps become integrally united with the remainder of the 20 article.

Heretofore the buckles and straps have ordinarily been assembled by hand which is a necessarily slow and accordingly expensive procedure. It is the object of this invention 25 to provide an apparatus by which this operation may be mechanically performed.

In accordance with this invention a rotatable and reciprocable feed device presents a buckle with its eye in alignment with a strap 30 end, a predetermined length of strap is inserted through the eye, the strap is cut off and the ends doubled over and united. By the use of this apparatus, not only is greater speed obtainable, but also a more uniform product.

The invention will best be understood when the following detailed description is read in connection with the accompanying drawings, in which:

40 Figure 1 is a side elevation of the machine. Figure 2 is a plan view of a dial upon which are mounted a number of buckle holding devices.

Figure 3 is a section on the line 3—3 of 45 Figure 1.

Figure 4 is a section showing a strap guide.

Figure 5 is a plan view of a punch and die for cutting off straps.

Figure 6 is a section through a buckle holding device.

Figure 7 is a perspective view of the same.

Figure 8 is an enlarged perspective of a feed finger.

Figure 9 is an end view of the dial slide with the dial removed. 55

Figure 10 is a side view of the strap guide.

Figure 11 is a perspective view of part of the same.

Figure 12 is a perspective view of the wiping rolls. 60

Figure 13 is a side view of the locking lever, and

Figure 14 is a sectional view of a holding device for a complementary buckle element. 65

The invention illustrated comprises an apparatus having a base plate 1 supported by a suitable frame or legs 2. Mounted on base plate 1 is a dial slide block 3 having fastened to its top a dial slide gib 4. A dial slide 5 is mounted in the dial slide gib 4 which forms a slideway permitting longitudinal movement of the dial slide. Revolvably mounted upon the dial slide is the ratchet wheel 30 which carries rigidly a spindle 5' and a locating pin 6'. A dial 6 is supported upon the ratchet wheel 30, being accurately positioned thereon by engagement of the pin 6' with a slot in the dial. Around the circumference of the dial in regularly spaced recesses 7 are six buckle holding devices 8. Raised ribs 7a surround each recess. Each of these holding devices (Fig. 7) comprises a frame 9, having on its sides projections 10 which fit into grooves in the recesses 7 and may be held in place by set screws 9' in the webs 7a, said set screws engaging the frame between the projections. A holding block 11, and a holding clamp 12 cooperate to hold the buckle 13 rigidly in place. A lever 16 actuates the clamp. The holding block 11 is shaped to fit the links 14 and 15 which connect the holding clamp 12 with the clamp lever 16. In Figures 6 and 7 the holding device is shown as formed to grip one of the complementary buckle elements 13, while in Figure 14 the holding device is formed to grip the other element 113. 70

It is obvious, however, that by substituting a different form of holding device the machine may be used for inserting straps in the eyes of any desired form of buckle or any other eyed part to which it is desired to attach a securing strap. 75

Mounted on the dial 6 is a bracket 16' carrying pivotally a locking lever 17 having at its lower end a curved portion 18. The buckles are placed in the holding device pref- 80

erably when it is in front of the lower portion of the locking lever. After the buckle is in place, the lever 17 is thrown over far enough for the lower portion 18 to come in contact 5 with the clamping lever 16 (shown in Figure 13), it being of sufficient length to push the lever 16 down and extending the links 14 and 15 and thereby locking the holding clamp 12 as shown in Figure 6. By the time this 10 has been done, the dial is ready to swing around to its next position.

At the completion of each assembly the dial in the present instance makes one-sixth of a revolution, there being six fixtures for holding the buckles. However, any desired number of fixtures may be used. The dial is primarily actuated by the cam 19 on the cam shaft 20, the roll 21 running on the cam 19 causing a pivotal movement of the arm 22 20 which is pivoted at 21^a to the base plate 1 and actuates link 22' to rock the lever 23 with respect to base plate 1 causing the desired movement of the pawl slide 24 (Fig. 9) in the ways 25. The slide 24 is connected to 25 the lever 23 by means of the link 26 which passes through the stud 27 and is fastened thereto on either side by the nuts 28.

The pawl 29 (Fig. 9) pivoted on the top of the pawl slide 24 is held in contact with 30 the ratchet wheel 30 by the spring 31. The cam 19 is so arranged that when the dial is positioned at the rearward portion of its longitudinal movement as viewed in Fig. 1, the pawl in one of the slots 32 in the ratchet 35 wheel 30 is drawn back by the slide 24 thereby turning the dial one-sixth of a revolution. In this way the next holding device is brought in line with the wiping rolls 33 (Fig. 12). The dial slide 5 is then actuated and 40 carries the dial forward far enough for that portion of the buckle extending from the holding device to pass through the rolls 33, thus placing the aperture in the buckle directly over the strap held by the guide 35. The rolls 33 are carried in spaced relation by 45 the springs 79 so that the buckle or the buckle and an attached strip of material serve to spring the rolls apart in moving through them. The dial is held from turning by the locking pawl 34 which engages the slots 32 50 in the ratchet when the slide moves forward and does not disengage until the slide is moved rearwardly. The locking slide 34 is actuated by one arm 117 of a bell crank pivoted on the dial slide 5, the other arm 118 55 of which extends downwardly so as to engage and disengage with shoulder 119 on the slide gib 4. A spring 120 acts to press the locking slide 34 forwardly into engagement 60 with slot 32. With the dial slide in its forward or right hand position as viewed in Fig. 1, the arm 118 is permitted to drop downwardly carrying the locking pawl into engagement with slot 32. Rearward movement of the slide causes the arm 118 to ride

upon the shoulder 119 thereby pressing the slide 34 out of the slot 32 after which the dial is free to be rotated. The dial slide 5 is actuated by the cam 105 through the arm 106 which is pivoted to the base plate 1 at 70 107. One end of the arm 106 is secured in a bifurcated portion of the slide by a pin 108 and the other end has a roll 109 which runs in a groove 110 in the cam 105. By this means the whole dial is drawn back after each 75 buckle and strap have been assembled.

The guide 35 for the strap comprises a bracket member 36 (Figs. 10 and 11) having a flange 37 through which it is bolted to the base 1. The strap feed slide 38 is held in the slide ways by the gib 39 which permit a vertical movement of the slide. The buckle strap is supplied from the roll 40 on which it is wound, through the strap guides 41 and 42, passes between the feed finger holder 44^b 80 and guide 44^a, and is held by the feed finger 43^a. Feed finger 43^a has a number of teeth, as shown in Figure 8, and these are held in contact with the strap 44 by the feed spring 45 which presses pivotally mounted lever 43^b 85 against finger 43^a, although not enough pressure is exerted to cause them to penetrate. When the eyed portion of the buckle has passed through the rolls 33 the slide 38 is driven upward by means of arm 46 fastened by the pin 47 to the lever 48 which is pivotally secured to the frame of the machine at 49 (Fig. 3). A roll 49' engages and is actuated by a groove in one face of the cam 73. At the completion of the upward movement 90 of the slide 38 a small upwardly extending portion of the strap held between the fingers 44^a and 43^b is passed through the aperture in the buckle. The vertical slide 50, which is positioned directly above the wiping rolls 100 33 in runways in a bracket 50^a carried by the base plate 1, then drops down a sufficient distance to allow the fingers 51 and 52 to close on the end of the strap in a manner hereinafter to be described. The movement 105 of the slide 50 is accomplished by means of the connecting rod 53 having the yokes 54 and 55 at its respective ends. The yoke 55 is fastened by the pin 57 to one end of the lever 56 which is pivoted to the shaft 58 and 110 which is connected at its other end to the roll 59 which runs in the groove 60 in the face of the cam 61 keyed to the shaft 20. Shaft 58 is carried in brackets from the under side of base plate 1. The yoke 54 is fastened to one end of a lever 62 (Fig. 3) pivoted at 63 and connected at its other end to the link 64 which is secured to the slide 50 by means of the stud 65 held in place by the nuts 66. The recess 67 in the bracket 50^a is to allow 115 for the upward and downward movement of the stud 65, with the slide 50. The finger 51 is keyed to the shaft 68 carried in slide 50 to permit it to close against the fixed finger 52. Integral with the finger 51 is a trip 120 125 130

rod 70 which extends outwardly into position to be actuated by the lever 74. The upper portion of the finger 51 has a V-shaped groove along its top which is engaged by the point 5 of the dog 69 when the trip rod 70 is pushed upward and the fingers are in open position. When the trip rod 70 is swung down the finger 51 closes against the fixed finger 52 causing the upper portion of finger 51 to 10 move outwardly until the edge 71 of the dog 69 comes in contact with the bevelled edge of the upper portion of the finger. By this means pressure exerted by the compression spring 72 against the shoulder of 15 the trip dog 69 keeps the fingers tightly closed. The finger 51 is primarily actuated by one face of the cam 73 through the trip rod 70, the lever 74, yoke 75, rod 76, yoke 77, lever 77' carried by the shaft 58, and roll 20 78, which runs in a groove in the face of the cam 73.

At the completion of the downward stroke of the slide the fingers are but a short distance above the aperture in the buckle. The wiping roll springs 79 are set a distance apart to permit the fingers to go between them. The strap guide having made its upward stroke, the protruding portion of the strap passes through the aperture in the buckle and between the fingers 51 and 52 which are immediately closed in the manner described above. The upward stroke of the slide draws the strap through the aperture in the buckle slightly more than one-half the length required. The strap is then cut off below the buckle by a V-shaped punch 80 and die 81 (Fig. 5), fastened by suitable means to the slides 82 and 83 respectively. The punch and die are held in alignment by the guide 25 plungers 84 and 85 which are fastened at one end to the slide 82 and which have a sliding fit in the bushings 86 and 86' in the slide 83. The die slide is controlled by the lever 87, pivoted at 88 to the base plate 1. Lever 87 30 at its upper end is fastened to the bifurcated member 89 by the pin 90 and has at its lower end the roll 91 which runs in the groove 92 of the cam 93. The punch slide is actuated in a like manner through the lever 94 pivoted 35 at 95 to the base plate 1. Lever 94 at its upper end is fastened into the bifurcated member 96 attached to the punch slide by pin 97 and has at its lower end the roll 98 which runs in the groove 99 in the cam 100.

Upon the backward movement of the dial slide 5, the end of the buckle 13 which is passed between the wiping rolls 33 and the strap which has been passed through the aperture therein are drawn back through the wiping rolls, thus doubling the strap and sealing the ends of the strap together by the pressure of the rolls upon the strap.

As each holding device 8 with assembled buckle and strap enclosed reaches a position 60 opposite the opening arm 101, the backward

movement of the slide causes the bent portion 102 of the opening arm to come in contact with the lever 16 of the holding device 8 thus automatically opening each device. Arm 101 is supported from base plate 1 by a 76 bracket 101'.

The machine is provided with both a hand wheel 103 at one end and a pulley 104 at the other for driving by power.

In Figure 14 a form of holding device is 75 illustrated adapted for use when buckle elements 113 complementary to the buckles 13 are being assembled. The holding device shown in this figure is provided with a separate holding block 111 and holding clamp 80 112 which may be substituted for the holding block 11 and the holding clamp 12 by simply removing the pins 114. The numerals 115 indicate projections on the holding block 85 designed to fit into the openings 116 in the elements 113 thus holding them in alignment and preventing them from slipping. No adjustment of the machine is necessary when the holding devices are changed. In practice it has been found that it is sometimes 90 more convenient for one holding device to be equipped with block and clamp to hold a part 13 and the next to hold a part 113, and so on alternately around the dial. It will be 95 readily apparent that the apparatus disclosed herein provides a means of assembling buckles and straps with a great saving of manual labor. Due to the greater speed at which the assembly may be mechanically performed a still further economy is made possible. 100

In the operation of the machine, the end 105 of a roll 40 of rubberized fabric is threaded through the machine to a position opposite the springs 79. Power is supplied to the shaft 20 to drive the cam wheels and thereby actuate the machine. For the purposes of description, the buckle is assumed to have been inserted in the holding device with the holding device carried forward on the slide 5 to the position shown in Fig. 1. The protruding end of the buckle has passed between and extends beyond the rolls or guides 33 so that an opening formed in the buckle is positioned in alignment with the course of travel of the end of the strip of rubberized fabric. The buckle is held in this position while the end of the strip of rubberized fabric is carried upwardly by the slide 38, passing through the opening of the buckle. The cam 60 now actuates the slide 50 to lower the jaws 51 and 52 into position to grip the protruding strip of material and the cam 73 actuates pivoted jaw 51 to clamp the strip against the jaw 52. Further rotation of the cam 60 returns the jaws to their uppermost position, pulling the strip of material with them. Jaw 51 is subsequently opened to release the strip by further rotation of the cam 73. The strip of rubberized fabric is 110 115 120 125 130

now severed between the die 81 and the punch 80 which are actuated respectively by cams 93 and 100. This leaves the buckle free to be drawn back together with its attached strip 5 through the wiping rolls 33 and this step is effected by operation of the cam 105 which draws back the dial slide 5. In this step the strap is folded about itself and its ends are pressed together. When unvulcanized rubberized fabric is used as the material of the strip, the folded portions are united into a unitary piece due to the tackiness of the material. When the dial has been drawn rearwardly, it is carried in rotary movement 10 in a counter-clockwise direction, as viewed from above in Fig. 1 by actuation of cam 19. Each rotation of the cam causes the dial to rotate one-sixth of a revolution. Continuation of the intermittent rotation carries the 15 holding device to a position opposite the arm 101 which operates to press the lever 16 rearwardly thereby releasing the grip of the holding means upon the buckle. The buckle is then removed manually and as this particular holding device is carried around to a 20 position opposite the curved portion 18 of the locking lever 17, a new buckle is placed between the holding block and clamp 12. Actuation of the lever 17 causes its lower portion to press lever 16 forwardly thereby locking the buckle in place, after which it is again 25 carried between the wiping rolls 33. In the operation of the machine, a buckle is placed in each one of the six holding means.

35 While the invention has been described as applied to the use of a strap formed of unvulcanized rubber coated fabric, it is evident that other strips of material can be used and some of the advantages of the invention 40 realized. In place of a buckle, it is contemplated to use any type of perforated article to which it is desired to attach a strip of material. The holding device can be suitably modified to receive the article.

45 While one embodiment of the apparatus has been disclosed in detail in the foregoing paragraphs it is to be understood that the invention is to be limited only by the following claims.

50 Having thus described my invention what I claim and desire to protect by Letters Patent is:

55 1. An assembling machine comprising presser means, reciprocable means for holding an article adjacent the presser means, means for inserting a strip of material into association with the article, and means for withdrawing the article through the presser means whereby the strap ends are folded.

60 2. An assembling machine comprising presser means, reciprocable means for holding an article adjacent the presser means, means for inserting a predetermined length of strap therein, means for cutting off the

strap, and means for simultaneously withdrawing the article through the presser means and folding over and uniting the strap ends. 65

3. An assembling machine comprising reciprocable means for holding and feeding an article, means for threading a strip of material through the article, means for drawing a predetermined length of the strip through the article, means for cutting off the strip, and means for folding over and uniting the strip ends. 70 75

4. An assembling machine comprising a means for holding a strap adjacent its end, presser means, reciprocable means for holding and presenting an article adjacent the presser means with its eye in alignment with the strap end, means for inserting a predetermined length of strap through the eye, means for cutting off the strap, and means for passing the article and strap through the presser means thereby folding over and uniting the strap ends. 80 85

5. An assembling machine comprising a rotatable and reciprocable feed device, means thereon for gripping an article, means for intermittently rotating and reciprocating the feed device, means for attaching a strap to the article during said rotary and reciprocating movements, and means for releasing the article and attached strap. 90 95

6. An assembling machine comprising a rotatable and reciprocable feed means having an article gripping device thereon, and means cooperating with the feed means during its movements for inserting a length of strap in each article and uniting the strap ends. 100

7. An assembling machine comprising a rotatable and reciprocable feed means having a plurality of article gripping devices thereon, and means cooperating with the feed means during its movements for successively attaching a length of strap to each article and then releasing the finished article. 105

8. An assembling machine comprising a rotatable and reciprocable feed means having an article gripping device thereon, strap supply means, and means cooperating with the feed means for inserting a predetermined length of strap in each article, cutting off the strap, doubling over and uniting the strap ends, and releasing the finished article. 110 115

9. An assembling machine comprising a rotatable and reciprocable feed means having a plurality of article gripping devices thereon, means for actuating each gripping device to hold an article, strap supply means, and means cooperating with the feed device during its movements for attaching a length of strap to each article and then releasing the same. 120 125

10. An assembling machine comprising a feed device having article gripping means, cooperating guides, the feed device being

- movable to insert an article held thereon through and beyond said guides, means for inserting a predetermined length of strap through said article, said feed device being then movable to withdraw the article and strap through said guides, whereby the strap ends are doubled over and united, and means for imparting said movements to the feed device.
- 10 11. An assembling machine comprising yieldingly cooperating guides, means movable to insert an article through and beyond them, means for disposing a predetermined length of strap through the article, said article inserting means being then movable to withdraw the article to thereby fold over and unite the strap ends, and means for actuating the article inserting and withdrawing means.
- 15 12. An assembling machine comprising a feed device having a plurality of article gripping means, cooperating guides, said feed device being rotatable to align an article gripping means and an article with said guides and longitudinally movable to insert the article through and beyond the guides, means for inserting a predetermined length of strap through said article, said feed device being then movable to withdraw the article and strap through said guides, whereby the strap ends are doubled over and united, and means for imparting the aforesaid movements to the feed device.
- 20 13. An assembling machine comprising cooperating guide means for holding an article, means for disposing a predetermined length of strap in such article, and means for inserting the article through and withdrawing it from said guide means.
- 25 14. An assembling machine comprising co-operating spring pressed guides for holding an article, aligned-reciprocable means for disposing a predetermined length of strap in such article, and means for inserting the article through and withdrawing it from said guides.
- 30 15. An assembling machine comprising a rotatable and reciprocable feed device, a plurality of article gripping means thereon, means disposed at one point in the rotation of the feed device for closing a gripping member on the article, means at another point in the rotation of the feed device for attaching a strap to the article, means at a third point for releasing the finished product, and means for rotating the feed device.
- 35 16. An assembling machine comprising means for holding an article and moving it in a rotary path, means for imparting a single reciprocation to the article at one point in its path, means for attaching a strap to the article during such reciprocation, and means for releasing the finished product at another point in its path.
- 40 17. An assembling machine comprising means for holding an article and moving it in a rotary path, means for imparting a single reciprocation to the article at one point in its path, means for inserting a predetermined length of strap in the article, cutting off the strap and folding over and uniting the ends of the strap during said reciprocation, and means for releasing the finished product at another point in its path.
- 45 18. An assembling machine comprising means for holding a strap adjacent its end, a reciprocable feed device, gripping means thereon, means for actuating the latter to grip an article, strap guiding and inserting means cooperating with the feed device, means for actuating the strap guiding means to associate the strap with the article, means for drawing a predetermined length of strap through the article, means for cutting off the strap, means cooperating with the feed device to double over and unite the strap ends, and means cooperating with the feed device to release the finished product.
- 50 19. An assembling machine comprising a feed device having article gripping means thereon, means for rotating the feed device, strap guiding and inserting means adjacent the feed device, means for intermittently reciprocating the feed device to align an opening in the article carried thereon with the strap guiding means or to withdraw the article, means cooperating with the strap inserting means for drawing a predetermined length of strap through the opening of an aligned article, means for cutting off the strap, means cooperating with the feed device to double over and unite the ends of the inserted strap, and means for releasing the finished product.
- 55 Signed at New Haven, in the county of New Haven and State of Connecticut, this 30 day of April, 1926.
